SWITCH BANK CONTACT CLEANER

Bertram D. Lorimer, Toronto, Ontario, Canada, assignor, by mesne assignments, to Northern Electric Company, Limited, Montreal, Quebec, Canada, a corporation of Canada

Application April 29, 1944, Serial No. 533,423

5 Claims. (Cl. 15—97)

1

This invention relates to cleaners and particularly to a cleaning device for burnishing switch bank contacts of automatic telephone systems.

The object of this invention is to provide a more efficient and economical power driven device for simultaneously burnishing a plurality of rows of switch bank contacts.

It has been the practice heretofore in cleaning contacts of switch banks, such as those of the step-by-step type, to employ a manually operated tool having a plurality of arcuate blades that are rotated oscillatably, as a unit, across the contacts. However, this method of cleaning contacts is slow, monotonous, and fatiguing to the maintenance man and as a result many attempts have been made to devise a satisfactory cleaning tool driven by mechanical means. These attempts have been only partially successful, in so far as applicant is aware, since the resultant mechanically driven devices are subject to both substantial vibration and unbalanced torque, thus not only being difficult to handle but also tending to force the device against the sides of the switch bank with damage thereto during the cleaning operation.

With respect to the unbalanced torque, it appears that this defect is inherent in the design of the above devices in that the cleaning blades, which in one type oscillate together as a unit and in another type rotate continuously in one direction, develop a substantial force upon touching the switch bank contacts. Consequently, it is necessary that the maintenance man counteract this force at every instant, particularly at the moment of reversal of the cleaning blades in the oscillating type of tool, in order to prevent damage to the switch bank.

Applicant has overcome the above disadvantages and, in carrying out the above object, has devised an improved power driven tool in which vibration is minimized and in which the forces acting on the blades are substantially balanced.

The feature which particularly distinguishes the device according to the present invention from those mentioned above, especially as regards the operation of the cleaning blades, resides in three eccentric cams disposed 120 degrees apart, each cam being coupled to a pair of oscillating blades through a pivotal lever. Vibration and unbalance of the blades are substantially reduced inasmuch as the torque produced by one pair of blades while moving to the right is balanced by the torque produced by another pair of blades moving to the left, the third pair of blades, at that instant, being in a neutral

2

position and therefore producing no effective torque.

This and other features of the invention will be more fully described in the following specification, taken in connection with the accompanying drawings in which:

Fig. 1 illustrates a plan view of a switch bank with a cleaning tool, made in accordance with the present invention, in engagement with the contacts thereof;

Fig. 2 illustrates a side view of the tool;

Fig. 3 illustrates an enlarged cross-sectional view taken along line 3—3 of Fig. 2 in which the relative positions of the eccentric cams and associated levers and cleaning blades are shown;

Fig. 4 is a sectional view, similar to that of Fig. 3, in which the travel of the middle cam and associated lever and blades is shown;

Fig. 5 is a sectional view taken along line 5—5 of Fig. 1;

Fig. 6 is a portion of the clutch mechanism taken along line 6 of Fig. 5;

Fig. 7 is a sectional view of the grille taken along line 7—7 of Fig. 3;

Figs. 8 and 9 are plan and end views, respectively, of a lateral cleaning blade guide for the grille; and

Figs. 10 and 11 are plan and end views, respectively, of an arcuate bearing member for the grille.

Fig. 12 shows a modified form of the tool.

Referring now to the different figures of the drawings, in all of which like parts are designated by like reference characters, a portion of a standard switch bank 10 is shown in which the usual ten rows of insulated terminals 11 are disposed in superposed layers. The terminals 11 are generally disposed in pairs, being separated by an insulating material 12, which projects inwardly beyond that of the terminals 11.

One end 13 of the terminal 11 is adapted for connection to wires (not shown) while the contact end 14 is adapted for engagement with the usual switch wiper spring (not shown). The surface of contact 14 collects dust and dirt and after a while the accumulation thereof introduces a variable high resistance when engaged by the switch wiper, so that crackling noises result in the telephone circuit. This is annoying during a telephone call, and, in order to keep the noise resulting from dirty contacts at a minimum, it is necessary periodically to clean all the switch bank contacts.

In general, applicant's invention comprises a pistol-shaped cleaning device 16 having six arcu-

ately-shaped cleaning blades 17, grouped into three cleaning pairs 18, 19, 20 and actuated oscillatably in a lateral arc by three levers 22, one for each pair, under control of three eccentric cams 23, 24, 25 in which the eccentricities are displaced angularly at 120 degrees.

With the eccentric cams 23, 24, 25 so disposed it can be seen, particularly in Fig. 3, that at the instant shown, outer cams 23 and 25 are in the extreme left and right positions, respectively, while intermediate cam 24 is in the middle lower position with the associated cleaning pairs 18, 19, 20 disposed left to right, respectively. During the next 120 degrees of rotation of shaft 72 (assuming the direction of movement is clockwise as seen in Fig. 3) cam 23 will shift its lever 22 through a full oscillation in one direction, and cams 24 and 25 will shift their respective levers 22, each through a half oscillation in the opposite direction. And for each succeeding change of 120 degrees a similar relation exists. Therefore, the forces set up by the rubbing action of the blades on the stationary terminals substantially balance each other, reducing to a minimum the force which the operator must exert on the handle of the tool to hold it in position.

While applicant has employed an eccentric cam displacement of 120 degrees with three groups of cleaning blades in the particular embodiment shown in Figs. 1 to 11, he is not to be restricted to this angular cam displacement, as other angles may be adapted for balancing purposes. For example, two cams may be employed having an eccentric displacement of 180 degrees as shown in Fig. 12 in which two groups of, or merely two, cleaning blades may be associated therewith.

In detail, applicant's cleaning device 16 comprises a handle 27 having a flange 28 at the upper end, preferably in the form of a casting, a rectangular case 28 mounted upon handle 27, and a plurality of blades 17 oscillatably supported in a grille 31 of the case 28.

Case 28 comprises a back 32, bottom 33, and side flanges 34, 36 (see Figs. 4 and 5), preferably in the form of a casting, fastened to flange 29 by screws 37 (one of which is shown), the bottom 33 and flange 36 having arcuate guard arms 38, 39, respectively, which conform with the shape of the cleaning blades 17, extending to the front, and a top member 41 seated on flanges 34, 36 in any suitable manner, such as by aligning pins 62 in the flanges 36, 33 and corresponding apertures (not shown) in the top member 41, and secured thereto by nut 43 threadedly engaged with stud 44, which is rigidly secured to bottom 33. Depressed tongues 46, 47 (Figs. 5 and 7), which extend frontwardly from top and bottom members 41, 33, respectively, provide depressions for a removable bearing cap 48, which will be explained hereinafter.

At the front end of case 28 is provided an arcuate grille 31 for slidably supporting the cleaning blades 17 in their oscillatory motion. The grille 31 comprises lateral guide members 49 (Figs. 8 and 9) and arcuate bearing members 51 (Figs. 10 and 11) assembled in a stack (Fig. 7) and secured to top 41 and bottom 33 of case 28 by bolts 52 and nuts 53.

Each of the cleaning blades 17 comprises an arcuate member, preferably of stamped steel, shaped to conform at the free end with the curvature of the rows of contacts 14 in the switch bank 18 and at the supporting end shaped to

conform with the arcuate faces of the bearing members 51 of the grille 31. A slot 54 at the supporting portion of blade 17 is provided for engagement with a roller 56 rotatably attached to lever 22 for reducing frictional wear between the blades and levers, while intermediate the ends of blade 17 serrations 57 are provided for securing thereto a cloth sleeve 58 of any suitable burnishing material and of such thickness that the cleaning blade 17 when so equipped fits snugly between the rows of contacts 14. A single cloth sleeve 58 is preferably employed for one pair of blades 17.

The supporting portions of the cleaning blades 17 are slidably disposed in interstices 59 formed by the lateral guide members 49 of the grille 31 and are held against the arcuate faces of the bearing members 51 by an arcuate bearing cap 48 having a U cross-section. The front portion 61 of cap 48 conforms in curvature with that of the front supporting portions of blades 17 and with the arcuate faces of lateral guide members 49. An arcuate bearing is thus formed for sliding movement of the blades 17 which are held to an oscillatory arc in conformity with the curvature thereof. The bottom and top members 62, 63, respectively, of cap 48 are adapted to be slipped over the front portions of the side flanges 34, 36, and tongues 46, 47, locking slots 64 (Fig. 1) being cut into both cap members 62, 63 for registration with pins 66 provided on flanges 34, 36 and bottom 33 (not shown). A slot 67 is also cut into upper cap member 62 for registration with latch pin 68 recessed in top member 41 and tensioned forwardly by a coiled spring 69, pin 68 being movable backward manually under control of a ball 71 having a shank (not shown) fixedly secured to pin 68. The cap 48 is thus locked in position by latch pin 68 and may be readily released by drawing ball 71 backwards, rotating the cap counter-clockwise and withdrawing it frontwardly until free of pins 68.

Assembled within case 28 are cams 23, 24, 25 either integral with or rigidly secured to a shaft 72, which is rotatably supported by cylindrical bearings 73, 74 secured suitably, such as by a press fit, in the bottom 33 and top 41, respectively. Cams 23, 24, 25 are embracingly engaged by a clevis 76 at one end of each of the levers 22, which are pivotally mounted on stud 44. Each of the levers 22 is tapered at the other end and is provided with a roller 56, which registers with slots 54 of a pair of blades 17. It is thus seen that the rotary motions of the eccentric cams 23, 24, 25 are translated by the levers 22 to oscillating translatory motions of the cleaning blade pairs 18, 19, 20.

To provide for a reduction in the cam speed, reducing gears 77 and 78, preferably have a ratio of 2 to 1. Gear 77 is fixedly attached to the cam shaft 72, and gear 78 is loosely mounted on driving shaft 79. Driving shaft 79 is rotatably supported by ball bearings 81, 82 secured suitably in the bottom 33 and top 41, respectively. It is, of course, understood that the gear reduction arrangement may be dispensed with and furthermore, the cams 23, 24, 25 may be mounted directly on the driving shaft 79. Additional ball bearings (not shown) are also provided in the handle 27 for insuring smooth rotation of driving shaft 79, which is driven by an external source of mechanical power (not shown), for example, a portable electric motor, coupled in any satisfactory manner, such as by a flexible shaft (not

shown) to a slot in the shaft 79 at the bottom of handle 27.

The clutch mechanism, as shown in Fig. 5, comprises protuberances 86 spaced radially around the lower surface of gear 78 and a coupler 87, having similar radially spaced protuberances 88, preferably as shown in Fig. 6. Coupler 87 is movable along shaft 83 by means of an axial slot 89 and shaft pin 91 combination under control of trigger 84, of usual shape, which has a rounded end 92 slidably disposed in a peripheral groove 93 of coupler 87. The trigger 84 is pivotally mounted on a pin 94 and is maintained in the release position by a spring tensioned pin 96. Manual operation of the trigger 84 forces the pin 96 inwardly and advances the coupler 87 along shaft 79, so that the protuberances 86, 88 intermesh and couple the shaft 79 to the gear 78. An extension 97 of shaft 79 is provided at the top of the device 16 in order to facilitate attachment thereto of the hereinbefore mentioned flexible drive shaft, which has a limited bending radius, in those instances where switch banks 10 are located near the floor. A fly-wheel 98 may be secured to the shaft extension 97 for balancing out backlash in the flexible drive shaft and clutch mechanism and also for further minimizing vibration in the cleaning device 16.

In the cleaning operation of a switch bank 10, the device 16 is first placed with the guard arms 38, 39, which are covered with an insulating material 99, pressed against the insulating members 12, that project inwardly beyond the contacts 14 to be cleaned, the cleaning pairs 18, 19, 20 being disposed in the interstices between the contact rows and bearing against the faces of the contacts 14. The driving shaft 79 of device 16 is then actuated, mechanically by a portable motor through operation of trigger 84, as previously described, eccentric cams 23, 24, 25 rotating therewith and levers 22 translating this rotary motion to an oscillating translatory motion in the cleaning pairs 18, 19, 20, which in turn sweep across the contacts 14 in the hereinbefore described manner. After the contacts 14 are satisfactorily cleaned, the mechanical power is disconnected by release of the trigger 84 and the device 16 is positioned to clean another section of the switch bank 10, the above operation being repeated. It is to be noted that no mechanical means is required to support the device 16 against the switch bank 10, the maintenance man merely supporting the tool 16 in position manually. Thus, by use of a tool of applicant's invention the cleaning operation is substantially expedited.

While this invention has been shown and described as embodying certain features merely for the purpose of illustration, it is, of course, understood that various modifications may be made in the details thereof and that the features may be applied to many other and widely varied fields without departing from the scope of the invention as defined in the appended claims. For example, the eccentric cam balancing feature may be applied to a cleaning tool in which the blades are reciprocating in a forward and backward direction.

What is claimed is:

1. A device for cleaning switch contacts comprising a supporting member, arcuate guides in said member, a plurality of cleaning blades mov-

ably secured in said guides for burnishing said contacts, said blades divided into three groups, a source of mechanical power and three cams for oscillating said groups of blades simultaneously in arcuate paths in such directions as to balance the torque developed by the movement of said blades over the surfaces of said contacts.

2. A device for cleaning switch bank contacts comprising a supporting member, arcuate guides in said member, a pair of cleaning blades movably secured in said guides for burnishing said contacts, a source of mechanical power eccentric cam means operated by said source and means controlled by said cam means for actuating said blades simultaneously in opposite directions in an arcuate path with a reciprocating motion across said contacts.

3. A device for cleaning switch bank contacts comprising a housing, a plurality of cleaning blades for burnishing said contacts secured in arcuate guides in said housing, said blades separated into three groups, a source of mechanical power, eccentric cam means coupled to each of said groups of blades and to said source of power, the eccentricities of said cam means being disposed at an angular displacement of 120 degrees, said guides, couplings and cams cooperating to impart to said blades reciprocating motions in arcuate paths in such phase relationship as to minimize the reactive forces encountered in burnishing said contacts.

4. A device for cleaning switch bank contacts comprising a housing, a plurality of cleaning blades journaled in arcuate guides in said housing for burnishing said contacts, said blades being divided into two groups, a source of mechanical power, and eccentric cam means coupled to each of said groups of blades and to said source of power for reciprocatingly actuating said blades in arcuate paths, the eccentricities of said cam means being disposed at an angular displacement of 180 degrees.

5. The combination in a cleaning device for use with an automatic telephone switch bank having superposed arcuate rows of contacts, said device comprising a housing, a shaft rotatably supported in said housing, a plurality of cams integral with said shaft, said cams disposed helically around said shaft at equal angular intervals, arcuate cleaning blades in said housing adapted for burnishing said contacts, pivotal levers interposed between said cams and said blades, and arcuate guides in said housing for directing said blades to and fro in arcuate paths, in response to the motion of said levers, to engage said arcuate rows of contacts.
